Attorney.

UNITED STATES PATENT OFFICE.

EARL LARKIN DAILY, OF MOUNT WASHINGTON, MISSOURI, ASSIGNOR TO HEMPY-COOPER MANUFACTURING COMPANY, OF KANSAS CITY, MISSOURI, A CORPORATION OF MISSOURI.

BABBITTING JIG.

Application filed May 16, 1921. Serial No. 469,795.

To all whom it may concern:

Be it known that I, EARL LARKIN DAILY, a citizen of the United States, residing at Mount Washington, in the county of Jackson and State of Missouri, have invented certain new and useful Improvements in Babbetting Jigs, of which the following is a specification.

This invention relates to improvements in babbetting jigs and while it may be employed to advantage in babbetting various articles, in the drawings I have shown it applied to a bearing such as constitutes a part of the cylinder block of an engine.

In its preferred form the invention embodies, among other features, a base plate adapted to fit directly upon the open flat side of the bearing to be babbitted and having openings through which the fluid babbitt may flow into the bearings, a die for placement within the bearing to mold the fluid babbitt to fit, or approximately fit, the shaft to be journaled in said bearing, means to grip and close the ends of the bearing, and prevent the fluid babbitt from flowing from said ends, and a rotary hopper which performs the triple function of directing the molten babbitt to the gates of the base plate, shearing off the surplus metal, and releasing the gripping means from the ends of the bearing.

In order that the invention may be fully understood, reference will now be had to the accompanying drawings, in which:

Fig. 1 is a plan view of the babbetting jig.

Fig. 2 is a side elevation partly in section of the jig.

Fig. 3 is an irregular section on line III-IV of Fig. 1, and in addition showing the jig on a bearing to be babbitted.

Fig. 4 is a detail perspective view of a base plate constituting a portion of the jig.

Fig. 5 is an inverted plan view of the jig.

Fig. 6 is a plan view of the jig in position upon an inverted cylinder block.

Fig. 7 is a vertical section of the jig.

In carrying out the invention, I employ a hopper 2 having a central vertical partition 4 dividing said hopper into two compartments 6, which taper downwardly to parallel gates 8 spaced apart and extending through the bottom of said hopper 2.

The hopper 2 is provided with a pair of

oppositely-disposed bosses 10 equipped with handles 12 whereby the hopper may be rotated upon a central axis consisting in the present instance of a stud 13 extending through the partition 4, the base plate 14 and a die 16 into which said stud 13 is threaded. Suitable means such as lock nuts 18 are threaded upon the upper end of the stud 13 to retain the hopper 2, the base plate 14 and the die 16 in assembled position.

The base plate 14 which is interposed between the bottom of the hopper 2 and the upper portion of the die 16, has a pair of parallel gates 20 which are spaced apart to register with the gates 8 in the hopper 20 when the latter is rotated to the position disclosed by Figs. 1 and 2. Two dowels 22 project from the underside of the base plate 14 to enter the bolt holes A in the bearing B, for the purpose of properly positioning the jig upon said bearing.

The die 16 is the same, or approximately the same, diameter as the shaft to be journaled in the bearing B, after the latter has been babbitted, but its upper half is 80 cut away to receive the base plate 14 and the lower portion of the hopper 2, so that when said base plate 14 rests upon the bearing B only the lower half of the die 16 will project into said bearing. When the die 16 is in position in the bearing B, a space C is left between the outer curved surface of said die and the inner surface of the bearing to receive the fluid babbitt which is to form the lining of the bearing. 90

The fluid babbitt is prevented from escaping at the ends of the bearing B by a pair of sleeves 24, which engage and close the ends of said bearing as disclosed by Fig. 3. The sleeves 24 are yieldably held in engagement with the ends of the bearing B by coil springs 26 interposed between collars 28 and the adjacent ends of the sleeves 24. The collars 28 are secured to the ends of the die 16 by suitable means 100 such as screws 30, so that they may be placed in position after the springs 26 have been placed upon the die 16.

The sleeves 24 are provided at their upper portions with antifriction rollers 32, 105 which are forced in opposite directions to disengage the sleeves 24 from the ends of the bearing B by diametrically opposed

cams 34 formed integral with or otherwise fixed to the hopper 2. The cams 34 have concentric surfaces 36 struck from the axis of the stud 13 and provided with recesses 38 to receive and hold the rollers 32 stationary, so that they in turn will hold the sleeves 24 in their outermost positions against the action of the springs 26 and allow the jig to be either placed in position 10 or removed from the bearing B.

In practice the sleeves 24 are forced apart to readily pass over the ends of the bearing B by grasping the handles 12 and rotating the hopper 2 on the stud 13 until the recesses 15 38 receive the rollers 32. The jig is then placed in position upon the bearing B where it is properly located by the dowel pins 22 entering the holes A. The hopper 2 is then rotated in a reverse direction to bring its 20 gates 8 into register with the gates 20 in the base plate 14, Figs. 1, 2 and 3, and to allow the springs 26 to force the sleeves 24 firmly into engagement with the ends of the bearing B. When the gates 8 register with the 25 gates 20 further rotation of the hopper 2 is checked by a shoulder 40 on said hopper contacting a stop 42 projecting upwardly from one corner of the base plate 14. The fluid babbitt is then poured into the two 30 compartments 6 of the hopper 2, preferably, with a two-spout ladle and flows into the space C, filling the same. The hopper is then rotated to the initial position to perform the dual function of shearing off the 35 surplus material above the gates 20 and spreading the sleeves 24 apart to disengage them from the ends of the bearing B, so that the jig can be easily lifted from said bearing. The entire operation is performed 40 in a very short time and good linings are insured as the fluid babbitt has no time to congeal before filling the space C.

While I have shown and described the preferred form of my babbetting jig, I reserve the right to make such changes in the construction, combination and arrangement of parts, as properly fall within the spirit and scope of the appended claims.

Having thus described my invention, 50 what I claim and desire to secure by Letters Patent, is:

1. In a bearing babbetting device, a base plate adapted to rest upon a bearing and having two gates spaced apart, a die secured to the underside of said base plate at a point between the gates and adapted to extend into the bearing to be babbitted, and rotatable means associated with the base plate to direct the fluid babbitt through the 55 gates and shear off the surplus babbitt.

2. In a bearing babbetting device, a member adapted to rest against a bearing and having an opening for the passage of fluid babbitt into said bearing, a die associated 60 with said member and arranged to extend

into the bearing to mold the fluid babbitt, elements adjustably mounted on said die to engage and close the ends of the bearing, and rotatable means associated with the member to direct the fluid babbitt through the gate and move said elements away from the ends of the bearing.

3. In a bearing babbetting device, a member adapted to rest against a bearing and having an opening for the passage of fluid babbitt into said bearing, a die associated with said member and arranged to extend into the bearing to mold the fluid babbitt, elements adjustably mounted on said die to engage and close the ends of the bearing, 75 springs to yieldably hold said elements in engagement with the ends of the bearing, and rotatable means associated with the member to direct the fluid babbitt through the gate and shear off the surplus babbitt. 80

4. In a bearing babbetting device, a member adapted to rest against a bearing and having an opening for the passage of fluid babbitt into said bearing, a die associated with said member and arranged to extend 90 into the bearing to mold the fluid babbitt, elements adjustably mounted on said die to engage and close the ends of the bearing, springs to yieldably hold said elements in engagement with the ends of the bearing, 95 rotatable means associated with the member to direct the fluid babbitt through the gate and shear off the surplus babbitt, and means associated with said rotatable means for disengaging the adjustable elements from the ends of the bearing simultaneously with the shearing off of the surplus babbitt. 100

5. In a bearing babbetting device, a base plate adapted to rest upon a bearing and having a pair of parallel gates spaced apart 105 for the passage of the fluid babbitt into said bearing, a die fixed to the underside of said base plate between the gates and arranged to extend into the bearing, axial means associated with the base plate, and a hopper 110 divided into two compartments for receiving and directing the fluid babbitt to the gates and rotatably mounted upon said axial means to shear off the surplus babbitt.

6. In a bearing babbetting device, a die, 115 means for positioning said die in a bearing, elements operably mounted on said die to close the ends of the bearing to prevent outflow of the fluid babbitt, a rotatable hopper associated with the die to direct the fluid 120 babbitt into the bearing, and cam means on the hopper to disengage said elements from the ends of the bearing when the hopper is rotated.

7. In a bearing babbetting device, means 125 for directing fluid babbitt into a bearing, a hopper rotatably mounted upon said means and through which the fluid babbitt is poured, elements associated with said hopper to yieldably close the ends of the bear- 130

ing, and cams fixed to the hopper to rotate therewith and move said elements away from the ends of the bearing.

8. In a bearing babbetting device, means for directing fluid babbitt into a bearing, a hopper rotatably mounted upon said means and through which the fluid babbitt is poured, a handle to said hopper, elements associated with said hopper to close the ends 10 of the bearing, springs to yieldably hold the

elements against the ends of the bearing, and cams fixed to the hopper to rotate therewith and move said elements away from the ends of the bearing.

In testimony whereof I affix my signature, in the presence of two witnesses.

EARL LARKIN DAILY.
